(57) **CLAIM**

The ornamental design for a faucet lever as shown and described.

DESCRIPTION

FIG. 1 is a perspective view of a faucet lever showing our new design;

FIG. 2 is a front view thereof;

FIG. 3 is a back view thereof;

FIG. 4 is a top view thereof;

FIG. 5 is a bottom view thereof;

FIG. 6 is a right side view thereof; and,

FIG. 7 is a left side view thereof.

The broken lines in FIG. 7 illustrate portions of the faucet lever and form no part of the claimed design.
